SYSTEM FOR ENERGIZING ELECTRICAL
PRECIPITATORS

Herbert J. Hall, Princeton, N. J., assignor to Research Corporation, New York, N. Y., a corporation of New York

Application June 19, 1950, Serial No. 169,019

6 Claims. (Cl. 183—7)

1

This invention relates to a system for energizing electrical precipitators and the like, and more particularly to a system in which the voltage applied to the electrodes of the precipitator is automatically regulated to provide a predetermined rate of sparking between the electrodes.

In the operation of electrical precipitators, contrary to previously accepted ideas, it has been found that optimum performance is attained when the voltage between the electrodes of the precipitator is maintained at a value substantially higher than that at which sparks start to jump between the electrodes. The sparks referred to are not the disruptive power arcs that sometimes occur between the electrodes, but are sparks of relatively low power that occur more or less frequently, depending upon operating conditions, and that do not put sudden serious overloads on the energization system. In an electrical precipitator, there is an optimum rate of sparking above and below which collection efficiency declines. Although the optimum sparking rate will vary for different precipitators, it typically is of the order of fifty to one hundred sparks per minute per precipitator section.

An object of the invention is to provide a system for energizing the electrodes of electrical precipitators that automatically sets and holds the voltage at a value corresponding to substantially optimum sparking rate.

Another object is to provide a relatively simple control system for automatically regulating voltage.

Another object is to provide in such a control system a device that counts each inter-electrode spark to form the basis for control.

The foregoing and other objects, as will more fully appear hereinafter, are typically achieved in a system for energizing the electrodes of an electrical precipitator including a voltage regulator, a device responsive to disturbances in the system caused by an inter-electrode spark, means for integrating the responses of the device, means responsive to the deviation of the integrand of the integrating means from a preselected value, and circuit elements operatively connected to the deviation responsive means for controlling the voltage regulator in accordance with the deviation determined by the deviation responsive means. The sense of control imposed by the deviation responsive means on the voltage regulator is determined by the sense of the deviation. The voltage control changes may be made in fixed steps at predetermined time intervals, or they may be in steps of variable degree applied

5 at variable time intervals depending upon the rate of deviation of the sparking rate from a preselected value.

In the drawing the figure is a diagrammatic view of a system in accordance with the invention for energizing an electrical precipitator including a control system.

Referring to the figure, the electrical precipitator indicated includes an extended surface collecting electrode 10, which may be in the form of a vertically disposed, grounded, metallic tube, and a fine wire discharge electrode 11 depending axially into the tube. These components are conventional and illustrative only. When the discharge electrode 11 is supplied with high tension current of the order of 60,000 volts, corona discharge occurs. Gas bearing suspended particles of material is passed through the tube 10 wherein the suspended particles are charged and deposited principally on the inner surface of the tube 10 from which the collected material is removed from time to time. In this well known manner, the gas is relieved of its suspended material.

10 20 25 Current for energizing the electrodes of the precipitator may be supplied by a source of alternating current 12 to the input terminals 13 of a switch 14. The output terminals 15 of the switch are connected to the end terminals 16 and 17 of an adjustable auto-transformer 18 having a control arm 19, adjustment of which varies the output voltage appearing across the terminals 17 and 20 of the auto-transformer.

30 35 40 A power transformer 21 has its primary winding 22 connected to the output terminals of the auto-transformer, through a surge-damping resistor 23. The secondary winding 24 of the power transformer supplies high voltage alternating current to a rectifier 25 that may be of any usual type such as a mechanical rotary switch rectifier or an electron tube rectifier.

45 One rectifier output terminal 26, preferably the negative terminal, is connected through a cable 27 to the discharge electrode 11 of the precipitator. The other output terminal 28 is grounded and thus is indirectly connected to the extended surface electrode 10 of the precipitator.

The energizing system, as thus far described, is merely illustrative, and other similar energizing apparatus having means for adjusting the voltage applied to the precipitator electrodes may be employed instead. In a characteristic embodiment, the current source 12 supplies 60 C. P. S. current at 440 volts which is stepped up by the power transformer 21 to about 60,000 volts.

Inter-electrode sparking in the precipitator may be sensed in a variety of ways. In the system shown in the figure, a capacitive device is employed. A capacitor plate 29 or similar pick-up element is placed adjacent the high tension cable 27 that carries current to the precipitator discharge electrode. Disturbances caused by a spark in the precipitator are reflected in the plate 29 as fluctuations in electric charge. The plate is connected to the control grid 30 of a glow tube 31 through a wire 32 that is shielded, as indicated at 33, and through a coupling network consisting of condenser 17 and resistor 18. The glow tube is gas filled and has a cold cathode 34, an auxiliary electrode 35 and an anode 36. A condenser 37 is connected across the glow tube to the cathode and anode of the latter.

A source of direct current 38, which may take the form of the battery shown, is used to charge the condenser 37. The battery is connected to the terminals of the condenser through the coil of a solenoid 39 and through a switch 40, the positive terminal of the battery being connected to that side of the condenser that is connected to the glow tube anode. When the switch is closed, a charge of fixed value is applied to the condenser. This charge is also applied across the glow tube, which is balanced to a point just below breakdown by the auxiliary electrode 35 and cooperating resistor 41 and by the control grid 30 and cooperating balance resistors 42 and 43. A slight increase in positive charge of the grid 30, such as is occasioned by an inter-electrode spark disturbance picked up through the capacitive coupling hereinbefore described, fires the glow tube 31 and discharges the condenser 37 very rapidly. The glow tube thereafter quickly becomes nonconducting and the condenser 37 is recharged by the battery through the coil of the solenoid 39.

The armature of the solenoid carries a pawl 44 that is drawn to the left, as seen in the figure, by the magnetic field generated by the solenoid coil during the time of flow of the condenser recharging current therethrough. This advances the ratchet wheel 47 one notch in a counter-clockwise direction.

The pawl 44 has a collar 45 engaging a leaf spring 46, whereby the spring is flexed as the pawl moves to the left. After the condenser is charged and the magnetic field of the solenoid has decayed, the spring 46 returns the pawl 44 to its normal position and exerts a downward pressure so that the pawl properly engages the next tooth in ratchet wheel 47.

It will thus be seen that the ratchet wheel 47 is advanced one notch for each spark that flashes between the electrodes of the precipitator. It will also be apparent that the glow tube-condenser-battery circuit, as coupled to the high tension electrode energizing system of the precipitator, may be considered as being a device responsive to disturbances in the charging system caused by an inter-electrode spark and that the solenoid-pawl-ratchet wheel system may be considered as being means for integrating the responses of the spark responsive device. Various equivalents of these elements of the control system may be employed without departing from the invention. For example, a resistance divider spark sensing device may be used instead of the capacitive type shown and described. A step-motor may be employed as an integrator instead of the solenoid-pawl-ratchet wheel motor illustrated. Various other equivalents will be readily apparent.

The control system of the invention also has a device responsive to the deviation from a pre-selected value of the integrand of the integrating means or motor referred to hereinbefore. This device includes a switch designated by the general reference numeral 48. The switch has a conductive arm 49 pivoted at 50, the free end of the arm being arranged to sweep across the complementary switch segments 51, 52 and 53 between the terminal stop members or abutments 54 and 55. A spring 56 biases the switch arm in a clockwise direction towards the starting position in which the arm abuts the stop member 54.

The switch arm is drivingly connected, as indicated at 57, to the ratchet wheel 47; this driving connection may include conventional speed-reducing gearing (not shown). The arm is also electrically connected to one side 58a of a source of current 58 through a wire 59, a sequence timer 60, a wire 61, a switch 62 and a wire 63.

Stop member 55 is carried by the swinging end of a lever arm, pivoted at 79, which operates switch 80 through a linkage 89. Switch 80, that is held in a normally closed position by spring 79a, is connected in series with the sequence timer 60 to solenoid device 72.

The opposite terminal 58b of the current source 58 is connected to the common terminal 64 of a reversing motor designated by the general reference numeral 65. This motor drives the adjustable arm 19 of the auto-transformer 18 through conventional mechanism, indicated at 66, that may include speed-reducing gearing. When one of the windings 61 of the motor is energized, the motor drives the adjustable auto-transformer in a direction to raise the output voltage of the latter; when the other motor winding 68 is energized, the motor is driven in a direction to lower the output voltage of the auto-transformer.

The segments 51 and 53 of the switch 48 are connected respectively to the separate ends of the motor windings 61 and 68 through wires 69 and 70. Segments 51 and 53 of the switch 48 are electrically conductive whereas segment 52 is electrically insulating. It will, therefore, be perceived that when electric power is applied between motor terminal 64 and the switch arm 49, three conditions are possible depending upon the position of the switch arm: (a) if the switch arm is in contact with segment 51, the motor is energized in the "raise voltage" direction; (b) if the arm is in contact with segment 53, the motor is energized in the "lower voltage" direction; and (c) if the arm is in contact with the segment 52, the motor is not energized.

Sequence timer 60 is conventional in construction and operation. It is supplied with current from the source 58 through wires 61 and 71 which energizes the timer motor and also provides electrical energy for activating the solenoid devices 72 and 73 at the proper time.

The solenoid device 72 has a link 74 extending from its armature to the blade of switch 40. Upon energization of the solenoid device 72, switch 40 is closed and upon deenergization, the switch returns to open position.

The solenoid device 73 has a link 75 extending from its armature, which link terminates in a loop 76 encircling the pawl 44 of the ratchet motor. When the coil of the device 73 is energized, the pawl is lifted from engagement with the teeth of the ratchet wheel 47, thus allowing the spring 56 to return the switch arm 49 and the ratchet wheel to starting position. Upon de-energization of the solenoid device 73, the pawl

44 is returned to operative engagement with the ratchet wheel under the action of gravity and the assistance of the leaf spring 46.

A manually operated switch 81 is provided for adjusting the setting of the auto-transformer control motor 65, whereby to vary the output voltage of the auto-transformer. This switch has a conducting arm 88, pivoted at 82, and co-operating contacts 84 and 86. Contact 84 is connected by wire 85 to wire 70; contact 86 is connected by wire 81 to wire 69; and switch arm 88 is connected by wire 83 to wire 63 that is connected to the terminal 58a of current source 58. To raise the output voltage of the auto-transformer, the circuit is closed between arm 88 and contact 86; to lower the voltage, the circuit is closed between arm 88 and contact 84. The arm 88 rests normally in the center position and is manually thrown to the "raise voltage" and "lower voltage" positions.

In operation, the switch 14 of the energizing system of the precipitator is closed and the auto-transformer output voltage is manually adjusted by operation of switch 81 to approximately the desired operating value. Switch 62 is then closed to energize the sequence timer 60 and the control system. It will be assumed that when the switch 62 is closed, the timing switches contained in the sequence timer 60 are in such position that switch 80 is closed, the solenoid device 72 is energized, whereby the switch 40 is closed, the solenoid device 73 is not energized, whereby the pawl 44 is in position to operate on the ratchet wheel 47, the arm 49 of the switch 48 is in starting position adjacent the stop 54, and no driving current is applied to the auto-transformer motor 65.

The spark responsive device including the glow tube 31 detects inter-electrode sparks as they occur in the precipitator. Each spark is registered by a one tooth advancement of the ratchet wheel 47, the motion of the ratchet wheel being transmitted to the arm 49 of the switch 48.

The sequence timer is so constructed and arranged that, after a predetermined period of time, solenoid 72 is deenergized to open the switch 40, thus de-energizing the spark counting system and stopping motion of the ratchet wheel 47. This time interval is selected with relation to other parameters of the control system such that if the number of sparks counted is the number corresponding to optimum precipitator operating conditions, the arm 49 is stopped at the mid-point of the insulated segment 52. Segment 52 extends over an arc of sufficient width to permit the arm 49 to be stopped in contact with this segment although the number of sparks departs from the optimum number by a reasonable margin. If the number of sparks counted in the period falls outside of the optimum range, the arm will come to rest on one of the terminal segments 51 or 53, depending on whether the sparking rate is lower or higher than optimum.

Next, the sequence timer directs motor driving current to the switch arm 49 for a predetermined short interval of time sufficient to activate the motor 65 to change the output voltage of the auto-transformer 18 by a substantially constant amount. If the switch arm is in contact with some portion of the segment 51, owing to a sparking rate less than optimum, the motor 65 will raise the voltage; if the arm is in contact with the segment 53, owing to a sparking rate higher than desired, the motor will lower the voltage. Of course, if the sparking rate has been

in the optimum range, the arm 49 will be in contact with the insulated segment 52 and no change in the output voltage of the auto-transformer will be effected.

Thereafter, the sequence timer energizes the solenoid 73 to disengage the pawl 44 from the ratchet wheel to allow the spring 56 to return the switch arm 49 and the ratchet wheel to starting position.

Next, the sequence timer cuts off the current flowing to the coil of solenoid device 73 and the pawl 44 reengages the ratchet wheel.

Finally, the sequence timer energizes the solenoid device 72 and switch 40 closes to begin the cycle anew.

Typically, the spark counting time interval may be about ten minutes and, although the control cycle may be repeated immediately, it has been found desirable to repeat the control cycle at intervals of about one-half an hour or one hour.

More frequent adjustment is ordinarily not necessary. Each step in the adjustment of the auto-transformer may effect a change of about one-half to one kilovolt in the potential of the current applied to the precipitator electrodes.

Under certain operating conditions, the sparking rate may be high enough for the arm 49 of switch 48 to complete its travel to stop member 55 before the end of the particular counting interval selected, in which event, the arm moves the stop member 55 in a direction to open the switch 80 and thereby to de-energize solenoid 72, thus opening switch 40 and shutting off the counter circuit, whereupon motion of ratchet wheel 47 stops. When this occurs, arm 49 remains in contact with segment 53 of switch 48 so that at the end of the selected counting interval, normal action of the sequence timer applies power to winding 68 to lower the precipitator voltage.

After the sequence timer has effected regulation of the precipitator voltage and has operated to return the switch arm 49 of switch 48 to starting position, the spring 79a returns the stop member 55 to normal position and closes the switch 80 to connect the solenoid 72 to the sequence timer 60 in readiness for a new control cycle.

From the foregoing description, it will be seen that the present invention provides a system for energizing electrical precipitators and the like that is responsive to sparking rate and that effectively maintains the sparking rate at or near the optimum value. Moreover, in the light of this description, alternative arrangements within the purview of the invention will occur to those skilled in the art.

It will be apparent that the control system of the invention may be employed in an electrical precipitation system wherein two or more electrical precipitator sections are energized from a common power supply controlled by a common voltage control system. In this case, each precipitator section has its own pick-up element coupled in common to the trigger circuit of the glow tube. Voltage control is thus responsive to the average sparking rate of the plurality of precipitator sections energized from the single power supply.

I claim:

1. A system for energizing the electrodes of an electrical precipitator comprising a voltage regulator, a device responsive to disturbances in the system caused by an inter-electrode spark, means for integrating the responses of said device, means responsive to the deviation of the integrand of said integrating means from a preselected value,

7
and circuit elements operatively connected to said deviation responsive means for controlling said voltage regulator in accordance with the deviation determined by said deviation responsive means.

2. A system for energizing the electrodes of an electrical precipitator comprising a voltage regulator, a device responsive to disturbances in the system caused by an inter-electrode spark, means for integrating the responses of said device, means responsive to the deviation of the integrand of said integrating means from a preselected value, and circuit elements operatively connected to said deviation responsive means for controlling said voltage regulator in a sense determined by the 15 sense of the deviation of said deviation responsive means.

3. A system for energizing the electrodes of an electrical precipitator comprising a voltage regulator, a device responsive to disturbances in the system caused by an inter-electrode spark, means for integrating the responses of said device over a predetermined period of time, means responsive to the deviation of the integrand of said integrating means from a preselected value, and circuit elements operatively connected to said deviation responsive means for controlling said voltage regulator in accordance with the deviation determined by said deviation responsive means.

4. A system for energizing the electrodes of an electrical precipitator comprising a voltage regulator, a device responsive to disturbances in the system caused by an inter-electrode spark, a motor actuated by said device for integrating the responses of said device over a predetermined period of time, a switch having a "raise voltage" position, a "neutral" position and a "lower voltage" position, means connecting said motor to

8
drive said switch progressively through said positions, and circuit elements including said switch for actuating said voltage regulator.

5. A system as defined in claim 4 including means for stopping said motor after a predetermined period of time and means for resetting said switch to starting position.

6. A system for energizing the electrodes of an electrical precipitator including a voltage regulator, a motor for actuating said voltage regulator, a multiple position switch, circuit elements connecting said switch with said motor to energize the motor in a sense determined by the position of the switch, a device responsive to disturbances in the system caused by an inter-electrode spark, a second motor for advancing said switch progressively through positions corresponding to "raise voltage," "neutral" and "lower voltage" actuation of the voltage regulator, said second motor being actuated by said device at a rate proportional to the responses of said device, and means for periodically energizing said circuit elements and said first motor through said switch and thereafter returning the switch to starting position.
